UNITED STATES PATENT OFFICE.

ADOLPH MACH, OF SPRINGFIELD, MASSACHUSETTS, ASSIGNEE TO PACKAGE MACHINERY COMPANY, OF SPRINGFIELD, MASSACHUSETTS, A CORPORATION OF MASSACHUSETTS.

WRAPPING-MACHINE.

1,289,216.

Specification of Letters Patent. Patented Dec. 31, 1918.

Application filed April 30, 1918. Serial No. 231,360.

To all whom it may concern:

Be it known that I, ADOLPH MACH, a citizen of the United States, and a resident of Springfield, in the county of Hampden and State of Massachusetts, have invented certain new and useful Improvements in Wrapping-Machines, of which the following is a specification.

This invention relates to improvements in wrapping machines and more particularly to machines wherein articles, such as chewing-gum, chocolate bars, soap, and the like, may be entirely inclosed in wrappers, as paraffin or wax-coated wrappers, and where 10 in such wrappers may be entirely sealed, as by fusing the paraffin coating on contiguous overlapped faces of the wrappers.

While the machine of the present invention constitutes in itself an operable wrapping machine for applying and sealing wrappers to articles, and is largely independent of the particular character of the articles, it is nevertheless capable of and adapted for use with the so-called multiple-stick wrapping machines, such as are shown 25 in U. S. Letters Patent No. 1,117,442, granted Nov. 17, 1914, to Redington and Milmoe, or in U. S. Letters Patent No. 1,133,668, granted March 30, 1915, to Redington and Milmoe. In the first-named patent, the multiple-stick package is entirely inclosed in an outer wrapper and placed in a swinging transport-arm which conveys the wrapped package into position for the application of an outer band or binder. The present invention deals largely with improvements which may be substituted for the swinging transport-arm of the machine shown in the first of the above-named 35 40 45 50 55 60 65 70 75 80 85 90 95 100

patents, to accomplish not only the function of conveying the wrapped articles to the banding mechanism, but also to permit certain desirable operations, as the sealing of the outer wrapper, to be performed prior to delivery of the package to the banding mechanism.

An object of the invention is to provide, in a wrapping machine of the type wherein articles delivered from one mechanism are carried to another mechanism by a swinging

transport-arm, a mechanism to be substituted for such arm to perform a complete wrapping operation during the passage of the article between the two first-named mechanisms, whereby an article or group of articles may be inclosed in an outer wrapper, and such wrapper sealed, if desired.

Another object of the invention is to provide in a wrapping machine, two swinging transport-arms which are arranged to swing simultaneously through an equal angle and are angularly as well as axially spaced, and a chute intermediate the path of such arms with which each may alternately aline, together with mechanism to transfer articles from one arm into the chute and subsequently to deliver such articles from the chute into the other arm.

A further object of the invention is to provide in a transfer chute of the class described, a combined folding and wrapper-sealing means, end-folding mechanism, and devices to seal the end folds, together with means to move the articles step by step through the chute to be operated upon successively by said means, mechanism, and devices.

A further object of the invention is to provide specifically improved end-folding mechanism for a wrapping machine.

A further object of the invention is to provide in a wrapping machine generally improved mechanical structure.

Other objects and advantages will appear in the following description and in the appended claims.

The invention, in an embodiment at present preferred, is shown for illustrative purposes in the accompanying drawings, in which—

Figure 1 is a front elevational view of a wrapping machine embodying the invention. Certain parts of the invention, particularly the wrapper-feeding mechanism, have been shown as broken away to reveal other and more important parts;

Fig. 2 is a sectional plan view taken on the line 2—2 of Fig. 1;

Fig. 3 is a cross-sectional view taken on the line 3—3 of Fig. 1;

Fig. 4 is an enlarged front elevational view of a part of Fig. 1, showing a different relative positioning of the conveyer-arms;

Fig. 5 is an elevational view, partly in section, looking at the right-hand end of Fig. 4;

Fig. 6 is a fragmentary elevational view taken on the line 6--6 of Fig. 5;

Fig. 7 is an end view of the conveyer arm;

Fig. 8 is an elevational view, partly in section, of the conveyer-arm;

Figs. 9 to 12 are perspective views illustrative of various steps in the wrapping of the articles;

Fig. 13 is an end elevational view of the fold breaking box; and

Fig. 14 is a perspective view of a portion of that part of the machine shown in Figs. 4 and 5.

The machine, in general, comprises an intermittently-operable swinging transport-arm having a folding box therein; suitable feeding mechanism operable while the arm is at rest in one position to position articles and their wrappers in such folding box and partially wrap the articles; devices operable during the movement of the arm to fold other portions of the wrappers about the articles; a stationary chute with which the folding box aligns when the arm comes to rest in another position; means to transfer the partially wrapped articles from the folding box into the chute and operable to apply other portions of the wrapper about the articles; oscillatory end-trucking fingers to complete the wrapping of the articles while in the chute; heating and cooling devices associated with the latter and operable successively on the wrapped articles as they pass through the chute, a second intermittently-operable swinging transport-arm arranged when it comes to rest in one position to align with said chute to receive a wrapped and sealed package therefrom and operable to carry the package to a delivery point or to other mechanism, such as banding mechanism, for example; and means to remove the package from the second arm when it comes to rest in its other position.

The general frame structure of the machine will first be described. Referring to Fig. 1, A represents a bed-plate suitably supported by a frame B. Rotatably mounted in the latter is a shaft 20, which may be driven in any suitable manner and is arranged to actuate the several mechanisms of the machine, as will appear. Such mechanisms are either mounted directly on bed A or indirectly by means of brackets attached to the bed. Thus, adjacent the rear of bed A (Fig. 2) and attached thereto are three upstanding brackets *a*, *b* and *c*, which are arranged in substantial alinement and in spaced relation. Bracket *a* supports the mechanism for transferring the articles from

the folding box of the swinging transport-arm into the sealing chute, as will appear, and this bracket, largely broken away in Figs. 1 and 2, appears more completely in Figs. 3 and 5. Bracket *b* supports the transfer chute, and is best shown in Figs. 4 and 5. Bracket *c* carries the oscillatory end-tuckers and is also best shown in Figs. 4 and 5. Forwardly of the brackets *a*, *b* and *c* is a pair of spaced upstanding brackets *d* (Figs. 1, 2 and 3) which are suitably mounted on bed A and rotatably support a wrapper-supply roll 21 with its axis in parallel relation with the main drive-shaft 20. Near the forward end of bed A and suitably fixed thereto is a bracket *e* (Figs. 1 and 2) which rotatably supports a drive-shaft 22 for the wrapper-feeding mechanism, and this drive-shaft is arranged parallel with shaft 20 which is suitably connected therewith, as by chains 23 and suitable sprockets. Substantially centrally of bed A and suitably fixed thereto is a table *f* on which the articles to be wrapped may be placed by any suitable means and adjacent the table and also fixed to bed A is a chute *g* which is alined with the table to receive articles therefrom. Slightly spaced from chute *g* is a second chute *h*, hereinafter called the fold-breaking box through which the articles and their wrappers may be fed.

The article-feeding mechanism will next be described with particular reference to Figs. 2 and 3. Such mechanism consists of a plunger 24 which is reciprocable along a line at right angles to the main drive-shaft 20 to carry the articles from table *f*, into and through both of the described chutes *g* and *h*. Plunger 24 is fixedly mounted on a bar 25 (Figs. 1 and 2) which is slidably supported on bed A forwardly of the described chutes *g* and *h*. Plunger 24 is actuated by a cam 26 on the main drive-shaft 20 (see Fig. 1) in the following manner: A lever 27, suitably fulcrumed on frame B, as indicated in Fig. 1, and having a roll to ride in a suitable path in cam 26, has its upper end connected by a link 28 to a lug on the under side of member 24. Cam 26 is so constructed as to move plunger 24 to the right (as viewed in Fig. 3) until its forward and article-engaging end lies substantially flush with the exit end of the described fold-breaking box *h* and then to return to the illustrated position.

It has been described that the articles may be delivered in any suitable manner to table *f*. When the machine is employed for wrapping multiple-stick packages, such as sticks of chewing-gum or the like, for example, the means for delivering the articles into position for engagement by plunger 24 may be of the type shown in the second of the above-named patents, and the table *f* may obviously be omitted, if desired, to permit

the articles to be moved vertically between the plunger 24 and chute *g*, as shown in such 5 though it is readily capable of use with such means as are shown in the last-named patent, if desired.

The wrapper-feeding means will next be considered with reference to Fig. 3. The 10 wrapping material in this instance consists of a paraffined or wax-coated paper, or any other suitable material which may be sealed by the application of heat. The wrapping material is supplied in a continuous strip *i* which is wound on the described roll 21. Strip *i* is led from roll 21 over suitable 15 guide-rolls 29 to and between a pair of coacting feed-rolls 30 and thence into a chute *j*. A second pair of coacting feed-rolls 31 20 are operable to grip the strip while in chute *j*, and from rolls 31 the strip passes downwardly through and below the chute *j* into the space between the chute *g* and fold-breaking box *h*. A knife 32 associated with 25 one of the rolls 30 is operable to sever the strip into wrappers of suitable length which may be carried with the articles into box *h*.

The invention is independent of the particular type of wrapper-feeding mechanism 30 employed, and that shown is given merely as an illustrative example of one known and suitable type. Since the invention is not concerned primarily with the wrapper-feeding mechanism and since such mechanisms 35 are now well known in the art, the present illustration has been confined largely to a conventional or diagrammatical showing of the wrapper-feeding mechanism. For example, the driving connections for rolls 30 40 and 31 have not been illustrated inasmuch as they are unnecessary to an understanding of the present invention, it being understood that rolls 30 and 31 may be geared up to the described shaft 22 to suitably feed 45 the wrappers *i*, without requiring the exercise of inventive skill.

The swinging transport-arm and its folding box will next be described. Referring first to Figs. 1 and 2, the transport-arm is 50 indicated by reference numeral 33 and is suitably connected at one end to a shaft 34 which is mounted for oscillation in suitable spaced bearings secured to bed A, as shown in Fig. 2. The shaft 34 is arranged with its 55 axis at right angles to the main drive-shaft 20 and passes through the described bracket *b*, as shown in Fig. 4. In Figs. 1 and 2 the transport-arm is shown in one of its positions of rest, wherein its folding box to be 60 described alines with and forms a continuation of the fold-breaking box *h*. In Fig. 5, the transport-arm is shown in its other position of rest in readiness for the delivery of the partially wrapped articles to the sealing 65 chute, as will later appear.

The detailed construction of the transport-arm 33 and its folding box is best shown in Figs. 7 and 8, to which reference will now be made. It has been mentioned that the arm 33 is suitably connected to shaft 70 34. Preferably, the arm is connected to the latter by means of a spring pressed plunger 36 which is constantly urged toward the shaft and normally engages a flattened portion 37 thereon for an operable driving engagement. With such construction, the arm 33 may be swung out of driving engagement with the shaft and moved into convenient position for adjustment or inspection of the folding box, when desired.

Near the outer end of arm 33, its upper face is suitably formed, as at 38, to constitute one wall of the folding box. Secured to the arm by studs 39 and arranged adjacent each end of the surface 38 are dovetail-shaped 85 blocks 40. The two spaced blocks 40 constitute the end walls of the folding box to engage the ends of the articles. Pivoted to arm 33 adjacent each block 40 and loosely encircling its stud 39 is a plate 41 which is 90 constantly urged toward its block 40 by a spring 42 coiled around stud 39. The free ends of the plates 41 extend toward one another and project beyond the blocks 40 to form yieldable top members for the folding 95 box to engage the top side of the article. The construction of the folding box is such as to afford recesses, as at 43, above and below each block 40 to receive end extensions of the wrapper, as will appear.

The fold-breaking box *h*, heretofore described in general terms only, may be constructed similarly to the folding box on arm 33. In the illustrated embodiment of the invention, as shown in Fig. 13, the only real 105 difference between the folding box *h* and the folding box on arm 33, is that in the former its top wall is composed of a single and vertically yieldable spring pressed plate *h'* instead of the two pivoted plates 41 described. 110 This difference, however, is not essential. It is preferred to adjust box *h* so that it functions preliminarily to the folding box on arm 33 to start or break the fold, leaving the final close application of the wrapper to the 115 transport-arm folding box. Obviously, box *h* may be entirely omitted, if desired, or it can be arranged to completely effect the folding function, leaving the transport-arm folding box as a mere carrier so fashioned as 120 to receive the end wrapper extensions of the partially wrapped article.

The transport-arm 33 is at rest in the position shown in Figs. 1 and 2 during the described feeding movement of the plunger 24. 125 The articles, such as the group of sticks *k* illustrated, or other single articles, if desired, are carried by the plunger 24 through chute *g* and against the wrapper *i*, which, it is to be understood, has hitherto been sev- 130

ered from its supply strip. Further movement of plunger 24 will carry articles *k* and the wrapper *i* into and through box *h* and into the folding box of the transport-arm.

5 Since the box *h* functions similarly to the transport-arm folding box, a description of the folding operations in the latter will suffice for both. It will be obvious that the wrapper on entering the folding box is engaged by the surface 38 and adjacent its ends by the top plates 41, which lay the wrapper about one side face and top and bottom faces of articles *k*, as shown in Fig. 9, leaving an extension *l* to be subsequently 10 folded against the other side face and later overlapped with the edge of wrapper on the bottom face of the articles. The wrapper is wider than the articles are long whereby there are other wrapper extensions to be 15 folded against the ends of the articles. The first fold of such end extensions is accomplished by the described blocks 40 which lay the wrapper against the articles, as indicated at *m* in Fig. 9, leaving upper and lower end 20 extensions *n* to be subsequently folded, which extensions are received in the described recesses 43. Although the plates 41 do not extend entirely across the upper face of the articles, they nevertheless extend sufficiently 25 to hold the upper portion of the wrapper while the end tucks *m* are being made. In making such end tucks, the tendency is to throw the portions *n* (Fig. 9) upwardly about the end edges of the articles as an axis.

30 Such upthrow is prevented by the engagement of the plates 41 both with the portions *n* as well as with the portions of the wrapper adjacent the portions *n* and overlying the articles. It is to be understood that the 35 folding operations may be accomplished in box *h* by parts exactly similar to those described in connection with the transport-arm folding box.

The transport-arm 33 is movable from the 40 position shown in Fig. 1 to that shown in Fig. 5 by the following mechanism: A pinion 44 (Fig. 2) is fixed to shaft 34, and in mesh therewith is a vertically-slidable rack-bar 45, the upper end of which is suitably 45 guided in frame A (Fig. 2). Referring now to Fig. 3, a bracket 46 secured to the lower end of the rack-bar 45 functions to hold the latter against the main drive-shaft 20 as a supplementary guide and is provided 50 with a roll to ride in a suitable cam-path 47 formed in one face of a cam-disk 48 secured to shaft 20. Cam-path 47 is so constructed as to swing arm 33 in a clockwise direction (as viewed in Fig. 1) after the partially 55 wrapped package has been deposited therein and to move the arm into the position shown in Fig. 5. The arm 33 is held thus positioned for an interval sufficient to permit removal of the package and then is swung 60 counterclockwise back into the position

shown in Fig. 1. As shown in Fig. 1, the lower face of arm 33 abuts bed A and thus arrests the arm when it becomes accurately aligned with box *h*, irrespective of continued movement of shaft 34, which is rendered ineffective by reason of the yieldable driving connection 36 and 37 described. Similarly, arm 33, when in its other position, abuts a stop 49 on the described bracket *b* (Figs. 4 and 5) for a like purpose.

The folding means operable during the movement of arm 33 will next be described. Referring first to Fig. 3, it will be seen that the wrapper extension *l* lies in the folding box *h* at the time when arm 33 commences to swing upwardly. Consequently, the top walls of folding box *h* function to partially lay extension *l* against the remaining side face of articles *k*, as the arm moves upwardly. The extension *l*, thus partially folded, is laid closely and flatly against the articles, as shown at *o* (Fig. 10) by a folding blade 50, leaving an extension *p* to subsequently be laid against the bottom face of the articles. The blade 50, as shown in Fig. 1, is attached to the described bracket *b* and, as shown in Fig. 3, lies in the path of the extension *l*, whereby the latter may be laid down as the arm moves into its upright position.

The chute into which the partially wrapped package is carried from arm 33 will now be described with particular reference to Figs. 4, 5, and 6. The described bracket *b* has a flat plate-like portion 51, one face of which aligns with the surface 38 on the arm 33 when the latter comes to rest in its upper position. Plate 51 constitutes part of one wall of the transfer chute, and the remaining part consists of a heater plate 52, which, as shown in Fig. 4, is set into a suitable opening in plate 51 near the entrance end thereof, leaving upper and lower slots 51'. Plate 52 may be heated in any suitable manner, for example electrically, and a conventional representation of an electric heating coil is shown at 53 in Fig. 4. The plate 52 has parts which loosely encircle two vertically-spaced studs 55, which are fixed to plate 51, and the plate 52 is yieldably held in the illustrated position, wherein stops 56 thereon abut the bracket *b*, by springs 57 which are coiled around studs 55. In Fig. 4, only the upper portion of the plate 52 is shown, and consequently only one stud, spring, and stop appear, but it will be readily understood that the lower end of member 52 is constructed similarly to its upper end, the lower end being purposely broken away to reveal other novel features.

Suitably fixed one above the other in vertically-spaced relation on plate 52 are two dovetail-shaped blocks 58 with which the described blocks 40 are adapted to align

when the arm 33 is in the position shown in Fig. 5. The lower block 58 has been shown as broken away in Fig. 4. Pivoted to the block 58 and loosely encircling studs 59 on the latter, are plates 60 (the upper plate being shown in Fig. 4 and the lower plate in Fig. 5) which are yieldingly held by coiled springs 61 against the blocks 58 and which function similarly to the described plates 41, as walls of a folding box. It will thus be seen that the parts 52, 58 and 60 constitute a folding box similar in every way to the transport-arm folding box, except that one wall thereof is adapted to be heated.

The package, as will later appear in detail, is adapted to move intermittently through the chute of which members 51 and 52 are constituent parts and is adapted to come to rest in three positions. In the first position, the package is held in the folding box portion of the chute between plates 52 and 60, and in the other two positions it is suitably held against plate 51. To hold the package against the latter, the described plates 60 have narrow right-angular extensions or fingers 62 which are disposed parallel with the plate 51 and are substantially equal in length to the width of the latter. The upper finger 62 has been broken away in Fig. 5 to reveal important structure therewith. The ends of the package are adapted to be engaged and held, while the package is in its second position, by narrow extensions or fingers 63, which, as shown in Fig. 4, are inset into the blocks 58 and, as shown in Fig. 5, extend to the right of the latter.

The fingers 63 are purposely made shorter than fingers 62, since other means are provided to engage the ends of the package, when it is in its third position, as will now be described. Referring to Fig. 6, pivoted to bracket *b* at 64 and in vertically-spaced relation thereon, are two arms 65, each of which has a surface 66 to engage an end of the package. A spring 67, connecting the two arms 65, yieldingly forces the surfaces 66 against the ends of the package and the arms 65 are adapted to be limited in their movement toward one another by their abutment with the plate 51. The surfaces 66 may be heated by any suitable means, as by electrical means, for example, and as an illustrated example, an electrical heating coil 68, indicated merely in conventional form, is provided in each of the described arms 65.

The means for removing the partially wrapped articles from the transport-arm 33 and for moving the articles step by step through the combined folding box, heating means and chute will next be described. Referring to Figs. 3 and 5, mounted in bracket 66 *a* for sliding movement in a path parallel

to the path of the article-feeding plunger 24, is a plunger 70 which carries a package-engaging plate 70'. The plunger is connected by a link 71 to the upper end of a lever 72, as best shown in Fig. 5. Referring now to Fig. 1, wherein the lever 72 is completely shown, it will be seen that the lever is pivotally supported from bed A on a stub-shaft 73. Fig. 3 also shows the mounting of the lever. As shown in Figs. 1 and 3, the lower end of lever 72 carries a roll to ride in a cam-path formed in the opposite face of the described disk 48 from the cam-path 47 already described.

Referring now to Fig. 5, the actuating means for the plunger 70 is so designed as to move it, shortly after the transport-arm 33 comes to rest in the position illustrated, until the forward and package-engaging face of plate 70' lies flush with the left-hand edge of the heater-plate 52. The plunger is arranged to dwell in this position, leaving the package in the heater, for a sufficient interval to allow the heater-plate 52 to effect its function, and then to advance to the right until the forward face of plate 70' lies substantially flush with the right-hand edge of plate 52, whereby the package is entirely removed from the heater and held in position against plate 51 by the fingers 62 and 63. The plunger then dwells in the last-named position while the transport-arm 33 is swung back to the position shown in Fig. 1, and the plunger 70, being less in width than the length of the space between plates 41, permits free movement of the transport-arm. As soon as the transport-arm 33 comes to rest in its horizontal position, the plunger 70 is again advanced to carry the package into its third position, in which it is engaged by the heated surfaces 66, and thereafter is retracted into the illustrated position before arm 33 is again swung upwardly. Similarly, on the next cycle of operation of the plunger, the package left in the third position will be removed therefrom and out of the chute into another device to be later described by abutment with a succeeding package as the latter enters the third position.

The means for completing the wrapping of the articles will now be described. It has been shown that the wrapper is folded as shown in Fig. 10, when the transport-arm comes to rest in the position shown in Fig. 5. It will also be apparent from Fig. 3, that the package in the folding box of the transport-arm will be pushed therefrom by plunger 70 in a direction opposite to that in which it was inserted by the article-feeding plunger 24. It has also been described that members 52, 58 and 60 constitute a folding box of similar construction to that in the transport-arm 33. Consequently, when plunger 70 removes the articles from the transport-arm, the wrapper extension *p* will be en-

gaged by plate 52 and laid against the bottom face of the articles. The edges of the wrapper then overlap and such overlapped edges, by engaging the heated plate 52 are joined together by the fusion of their wax coatings in a now well-known manner. Coincidentally with the folding of extensions n , end folds, as at q in Fig. 11, are made by the blocks 58, and such end-folding operations leave the upper and lower end wrapper extensions n in the form shown in Fig. 11. The extensions n lie in recesses 74 formed by the dovetail construction of blocks 58.

15 After the overlapped seam of the wrapper on the under face of the package has been sufficiently heated, the plunger 70 moves the package into its second position, wherein it is engaged by plate 51. The latter functions 20 to cool the heated portions of the wrapper and thus set the fused coating material. The pairs of end wrapper extensions n then lie on opposite sides of a finger 63 and project therebeyond ready for folding in a manner 25 to be described.

It has been shown that the package ejected by plunger 70 is left in the position just described until the transport-arm 33 moves into its horizontal position. Consequently, the folding of extensions n may advantageously be accomplished by means which are actuated from the transport-arm actuating mechanism itself. To this end, the reciprocable rack-bar 45, already described 35 as actuating the transport-arm, has an upwardly-extending bar 75 thereon which is suitably fixed to a block 76 mounted to reciprocate vertically in suitable ways formed in the upper part of the described bracket c , 40 as best shown in Figs. 4 and 5. The bracket c has a portion r , which is forwardly arched over and spaced from the slidable block 76, as shown in Figs. 4 and 5, to afford a bearing for one end of a shaft 77, the other end 45 of the shaft being journaled in the main portion of bracket c as shown in Fig. 5. Fixed to the shaft 77 and adjacent the portion r is a depending arm 78 which lies in back of the plate 51 and is offset as indicated 50 so as to lie directly behind that portion of plate 51 which is occupied by the package when in its second position. The slots 51' already described are extended as indicated in Fig. 5 to permit the entrance of two 55 spaced fingers 79 on arm 78, which fingers are so spaced as to simultaneously engage an upper and a lower extension n and fold it over the described fingers 63 which engage the ends of the package. Loosely mounted 60 on shaft 77, with its hub contiguous with that of the arm 78, is an arm 80 which extends downwardly to lie in front of the plate 51. Arm 80 has two spaced end-tucking fingers 81 projecting therefrom toward the 65 fingers 79 and the fingers 81 are movable

similarly to the latter but in a reverse direction to lay the remaining upper and lower extensions n against the fingers 63 and in overlapping relation with the first folded extensions n .

70 Arm 80 has an upward extension 82 and fixed to shaft 77 beyond arm 80 is an upwardly-extending arm 83. The members 82 and 83 carry rolls which ride in cam-paths 84 and 85, respectively, formed in the reciprocable block 76 so that on sliding of the latter the arms 80 and 78, respectively, will be actuated. As shown in Fig. 4, the cam-paths 84 and 85 are so constructed that their respective arms 80 and 78 are both held in 80 their outermost positions, while arm 33 is in its vertical position, to permit free passage of the upstanding end folds n from the first into the second position of the package. It will also be noted that the rack-bar 45 moves 85 upwardly to swing the transport-arm 33 from the position shown in Fig. 5 to that shown in Fig. 1. The cam-block 76 will thus be moved upwardly, and cam-path 85 is so constructed as to move its arm 78 inwardly 90 so that its fingers 79 enter slots 51' and make the end folds described, during the first half of the interval required to return the transport-arm into the position shown in Fig. 1. It will be obvious from an inspection of Fig. 95 4 that the cam-path 84 is so constructed that its arm 80 is held stationary during the interval described. In the second half of the interval required to move the transport shown in Fig. 1, both cam-paths 84 and 85 100 are constructed so as to swing their arms 80 and 78 in the same direction—namely, clockwise, as viewed in Fig. 4. Thus, fingers 79 will be carried away from the ends of the package while fingers 81 move into engagement therewith. It is to be noted that the arms 80 and 78 also move in unison so that the fingers 81 and 79 which now almost touch each other are carried in this relation while the second pair of extensions n are being 110 folded. Thus, the first extensions n are held until the second extensions n may be laid by fingers 81 in overlapping relation against them.

115 Thus, at the time when transport-arm 33 arrives in the position shown in Fig. 1 and during its period of rest in this position, the overlapped folds n are held by fingers 81. It has also been described that while the transport-arm 33 is at rest in its horizontal 120 position, the plunger 70 is advanced to remove the package, the end folds of which have just been completed, into position to be engaged by the surfaces 66. In thus moving the package, its end folds are held in position during the transfer by fingers 81, so that folds n ride smoothly in under the surfaces 66. It is therefore particularly useful and advantageous to have the fingers 81 125 dwell in their inner position during the de- 130

scribed transfer of the articles, but after such transfer the dwell of the fingers 81 is no longer useful and, if continued, would interfere with free passage of the upstanding end folds n of an incoming package. It thus becomes essential to spread apart arms 78 and 80 into the positions illustrated in Fig. 4.

Such positioning of arms 78 and 80 is accomplished in the following manner: As the transport-arm 33 starts upwardly, rack-bar 45 moves downwardly and thus moves block 76 downwardly. This results in a reversal of the described movements of arms 78 and 80. That is, the fingers 81 are carried out of slots 51' and away from the plate 51, while the fingers 79 advanced toward plate 51, without, however, performing any useful function. As the transport-arm 33 arrives half way on its upward swinging movement, the fingers 81 are in their outer positions, while fingers 79 are in their inner positions, and during the latter part of the upward swinging movement of transport-arm 33, the fingers 81 are held in their outer positions while fingers 79 are gradually moved outwardly into the position shown in Fig. 4.

After the described operations of the end-tucking fingers, the plunger 70 is actuated to advance the package from its second and end-folding position to its third position, wherein the overlapped end folds n are engaged by the heated surfaces 66, whereby the wax coatings of the wrapper may be fused to seal the overlapped end folds. Due to the several thicknesses of the wrapper at the ends of the package, a longer interval of heating is required than is necessary for the overlapped longitudinal seam in the wrapper. This is accomplished by leaving the package in the third position, to be removed therefrom by abutment with a succeeding and incoming package, rather than to remove the package directly by the plunger. Thus, the package remains on plate 52, but a short interval, but the package is held by arms 65 during one complete cycle of operation of the machine, whereby the end folds m and n may be thoroughly heated to obtain a firmly sealed joint.

The means for carrying the wrapped and sealed packages from the end-fold sealing devices will now be described. Such means consists simply of a second transport-arm 87 which is yieldably connected to shaft 34 in the same manner as the transport-arm 33. The arm 87, however, merely has two opposed pairs of jaws 88 between which the wrapped and sealed package may be inserted, as shown in Fig. 4. As shown in Fig. 5, arm 87 is mounted on the opposite side of bracket b from arm 33 and is mounted at right angles to the latter so that when arm 33 is in the position shown in

Fig. 1, arm 87 is in upright position and jaws 88 form a continuation of the chute described. Thus, the package removed from the end-fold sealing devices is positioned in arm 87, and the surfaces 89 thereof act to cool the heated portions of the wrapper and set the fused coating material thereof. It has been described that, while the transport-arm 33 is positioned horizontally, the plunger 70 advances on its third step of movement to carry a package from the end-folding mechanism into the end-fold-sealing devices. At such time, the arm 87 is at rest and positioned vertically so that the package in the end-fold-sealing devices is moved by abutment with the incoming package into the jaws 88 of arm 87. Thereafter, the latter is swung downwardly as arm 33 swings upwardly to carry the wrapped and sealed package s into the position shown in Figs. 8 and 4.

The package s may be removed from the transport-arm 87 by any suitable or desirable means. For example, the means shown in the first of the above-named patents may be employed to remove the package to suitable banding mechanism, such as shown in such patent, or any other suitable type of ejecting means may be employed to deliver the package to any other suitable mechanism for the invention is independent of the particular mechanism to which the wrapped and sealed packages are delivered. In the drawings, there has been shown a table 90 upon which the arm 87 comes to rest in its lower position, and as an illustrative example of one operable, although not necessarily preferred, means for removing the packages s from arm 87 and depositing them upon table 90, the following means have been illustrated: Referring to Fig. 2, a plunger 91 is mounted to slide on a guide-bar 92 fixed to bed A, in a direction parallel with those plungers heretofore described. A lever 93, fulcrumed intermediate its ends 110 on the described stub-shaft 73, has its upper end connected by a link 94 to the plunger. Referring now to Fig. 1, the lower end of lever 93 carries a roll which rides in a suitably designed path-cam 95 fixed on the main drive shaft 20. Cam 95 is constructed to actuate lever 93 through one complete cycle, while the arm 87 is at rest in its horizontal position. Thus, the plunger may be advanced to eject packages s on table 90 and thereafter retracted into the illustrated position before arm 87 commences its upward swinging movement.

The operation of the machine will now be briefly summarized. Articles to be wrapped, either singly or in groups, as desired, are fed against wrapper t , into and through the fold-breaking box h and into the folding box of the transport-arm 33, while the latter is at rest in its horizontal position, by the

plunger 24, which is thereafter retracted into the illustrated position and held in such position until the transport-arm completes one complete cycle of operation. Thus, the 5 wrappers *i* are applied to the articles in the form shown in Fig. 9. The arm 33 is then swung upwardly and, as it moves into its vertical position, the blade 50 lays down the wrapper extensions *l*, the wrapping then appearing as shown in Fig. 10. After arm 33 10 has come to rest in its vertical position, plunger 70 is advanced to carry the article and wrapper into the combined folding box and heater, and, as they enter, plate 52 and 15 blocks 58 act on the wrapper as described, leaving the wrapping in the condition shown in Fig. 11. At the same time, the plate 52 fuses the wax coating of the longitudinal overlapped seam in wrapper *i* and after the 20 elapse of a sufficient interval for this function, the plunger 70, which has been held stationary during such operations and the latter occur while the arm 33 swings downwardly into position to receive another article and its wrapper. During such interval, the fingers 79 are first moved inwardly to 25 lay down one upper and one lower extension *n* and then the fingers 81 are moved inwardly to lay down the remaining extensions *n*, while the fingers 79 retract in such a manner that the first folds *n* are not released until the second folds *n* have been overlapped upon them. The fingers 81 remain in their inner positions to hold folds *n* while arm 33 is at rest in its horizontal position. During such period of rest, the plunger 70 is advanced its third and last step 30 to carry the more completely wrapped package into the end-fold-sealing devices and to remove from such devices into the arm 87, which is now at rest in its vertical position, the package heretofore positioned in the end-fold-sealing devices. The plunger 70 is then retracted before arm 33 brings a 35 succeeding article and its wrapper into position for insertion in the transfer chute. Meanwhile, a package remains in the end-fold-sealing devices for a complete cycle of operation of the machine, whereby the heated surfaces 66 may have ample time to effectively join the overlapped end folds 40 *m* and *n*. The sealed package ejected into the transport-arm 87 is carried to table 90, and while the arm dwells in such position, the package is ejected by the plunger 91.

Thus, I have provided an operable wrapping machine in which an article or group of articles may be entirely inclosed in a wrapper and such wrapper entirely sealed. Furthermore, I have provided a mechanism which may advantageously be interposed in known forms of gum-wrapping machines be-

tween the stick-grouping and package-handing mechanism to effect a similar function.

It is recognized that modifications may be made in the one embodiment of the invention herein described for illustrative purposes without departing from the scope of the invention, which is defined by the appended claims rather than by the foregoing description.

What I claim is—

1. In a wrapping machine, two members mounted to simultaneously move in constantly-spaced relation and in spaced parallel planes, means to intermittently move each member to and from a position in a common plane intersecting the first-named planes, a guideway extending between the latter and disposed in the common plane, article-receiving pockets provided in each member and arranged to alternately aline with said guideway, and means to move an article from one member into said guideway while such member is at rest in the common position and to subsequently move the article from the guideway into the other member after the latter comes to rest in such common plane.

2. In a wrapping machine, two members mounted to simultaneously swing in angularly-spaced relation and in spaced parallel planes, means to intermittently move each member to and from a position in a common plane intersecting the first-named planes, a guideway in such plane and extending between said planes, article-receiving pockets provided in each member and arranged to alternately aline with the guideway during periods of rest of said members, and means to move an article from one member into the guideway and to subsequently transfer such article from the guideway into the other member.

3. In a wrapping machine, two members mounted to simultaneously move in constantly-spaced relation and in spaced parallel planes, means to intermittently move each member to and from a position in a common plane intersecting the first-named planes, a guideway extending between the latter and disposed in the common plane, article-receiving pockets provided in each member and arranged to alternately aline with said guideway, means to move an article from one member into said guideway while such member is at rest in the common plane and to subsequently move the article from the guideway into the other member after the latter comes to rest in such common plane, and means to operate on the articles while in said guideway.

4. In a wrapping machine, two members mounted to simultaneously move in constantly-spaced relation and in spaced parallel planes, means to intermittently move each member to and from a position in a common plane intersecting the first-named

- planes, a guideway extending between the latter and disposed in the common plane, article-receiving pockets provided in each member and arranged to alternately align 5 with said guideway, means to position articles and their wrappers in the pocket of one member while it is at rest in another position and operable to partially wrap the articles, means to move an article from the 10 last-named member into said guideway while such member is at rest in the common plane and to subsequently move the article from the guideway into the other member after the latter comes to rest in such common 15 plane, means to complete the wrapping of the articles while in said guideway, and means operable while the articles are in the latter to seal their wrappers.
5. In a wrapping machine, spaced devices 20 upon one of which articles may be received from one mechanism and upon the other of which articles may be delivered to another mechanism, and means to convey the articles from the first to the second device and 25 to wrap the articles during their passage between said devices, said means comprising a folding box into which an article and its wrapper may be forced in one direction to partially wrap its sides and ends, means to 30 move said box to another position, a guideway with which the first box alines when in such position and into which the articles may be moved in an opposite direction, said guideway including a second folding box 35 operable to complete the wrapping except for end extensions, end-folding mechanism to complete the wrapping of the articles while in said guideway, a conveyer-arm movable between the guideway and the second device 40 to receive the articles from the former and deliver them to the latter, actuating means to move the articles into the first folding box, actuating means to move the articles into and through said guideway and into the conveyer-arm, 45 actuating means to remove the articles from the latter, and coördinating mechanism connecting the several actuating means to cause them to operate in properly-timed relation.
6. In a wrapping machine, spaced devices 50 upon one of which articles may be received from one mechanism and upon the other of which articles may be delivered to another mechanism, and means to convey the articles 55 from the first to the second device and to wrap the articles during their passage between said devices, said means comprising a folding box into which an article and its wrapper may be forced in one direction to 60 partially wrap its sides and ends, means to move said box to another position, a guideway with which the first box alines when in such position and into which the articles may be moved in an opposite direction, said 65 guideway including a second folding box op- erable to complete the wrapping except for end extensions, end-folding mechanism to complete the wrapping of the articles while in said guideway, 70 a conveyer-arm movable between the guideway and the second device to receive the articles from the former and deliver them to the latter, actuating means to move the articles into the first folding box, actuating means to move the articles into and through said guideway and into the conveyer-arm, 75 actuating means to remove the articles from the latter, and coördinating mechanism connecting the several actuating means to cause them to operate in properly-timed relation.
7. In a wrapping machine, two article-receiving members mounted to move back and forth in constant spaced relation and in spaced parallel planes, pockets formed in 80 each member into which articles may be fed in a line at right-angles to the plane of movement of said members, a guideway extending between said planes and disposed in a plane at right-angles thereto, means to move said members from a position wherein the pocket in one member connects with one end of said guideway to a position wherein the pocket in the other member connects with the other end of the guideway, transferring 85 means movable through the pocket in one member while the latter is at rest adjacent said guideway to transfer an article into the latter and remain in its moved position until the other member comes to rest 90 with its pocket adjacent the other end of said guideway, said transferring means arranged to then move an article into the second member and to return into its original position before the first member again moves 95 into position adjacent said guideway.
8. In a wrapping machine, a guideway in which articles and their wrappers may be positioned for a wrapper-folding operation, an intermittently-swinging arm to carry 100 partially wrapped articles, mechanism to move the arm from one position to a second position and back again, means to position articles and their wrappers in said arm while it is at rest in the first position, means 105 operable while the arm is at rest in the second position to transfer the wrappers to said guideway for the folding operation, and folding mechanism connected to the first-named mechanism to operate during the 110 movement of the arm on the partially wrapped articles in said guideway.
9. In a wrapping machine, a guideway in which articles and their wrappers may be positioned for a wrapper-folding operation, 115 an intermittently-swinging arm to carry partially wrapped articles, mechanism to move the arm from one position to a second position and back again, means to position articles and their wrappers in said arm while 120

- it is at rest in the first position, means operable while the arm is at rest in the second position to transfer the wrappers to said guideway for the folding operation, two 5 folding members one on each side of said guideway and normally held in spread-apart relation, mechanism connecting said fingers and first-named mechanism so that the members are moved to folding position during 10 the movement of the arm from the second to the first position and so that one member is left in folding position when the arm comes to rest in its first position, and means to remove the articles from said guideway while 15 the arm is at rest in the first position, said connecting mechanism arranged to move said members into spread-apart relation while the arm moves from the first to the second position.
- 20 10. In a wrapping machine, a guideway in which partially wrapped articles may be positioned with oppositely disposed wrapper extensions to be folded one upon the other in overlapping relation, a pivoted folding finger mounted to swing into the path of one of said extensions and fold the latter, a second and oppositely arranged pivoted folding finger mounted to swing into the path of the other extension and fold 25 it, and a single actuating means engageable with both said fingers to coördinate their movements, the one relatively to the other, so that the first finger makes its fold and then moves back simultaneously as the second finger advances to make its fold, whereby the first extension is held until the second is overlapped upon it.
11. In a wrapping machine, a guideway in which partially wrapped articles may be 30 positioned with oppositely disposed wrapper extensions to be folded one upon the other in overlapping relation, a pivoted folding finger mounted to swing into the path of one of said extensions and fold the latter, a second and oppositely arranged pivoted folding finger mounted to swing into the path of the other extension and fold it, and a single reciprocable member having a cam to actuate each finger, said cams being 35 so arranged with relation to one another that the first finger makes its fold and then moves back simultaneously as the second finger advances to make its fold, whereby the first extension is held until the second is overlapped upon it.
12. In a wrapping machine, a guideway in which partially wrapped articles may be 40 positioned with oppositely disposed wrapper extensions to be folded one upon the other in overlapping relation, a pivoted folding finger mounted to swing into the path of one of said extensions and fold the latter, a second and oppositely arranged pivoted folding finger mounted to swing into the path of the other extension and fold it, and a single reciprocable member having a cam to actuate each finger, said cams being 45 so arranged with relation to one another that the first finger makes its fold and then moves back simultaneously as the second finger advances to make its fold, whereby the first extension is held until the second is overlapped upon it.
13. In a wrapping machine, means to partially wrap the sides and ends of articles, a guideway into which articles thus wrapped may be positioned, said guideway including a folding box operable to complete the 50 wrapping of the articles except for a pair of oppositely-disposed extensions from each end of the article and to form a longitudinal overlapped seam in the wrapping, means to heat that wall of the folding box contiguous with said seam, mechanism to fold said extensions and arranged adjacent said folding box, devices adjacent said mechanism to engage and hold the folded extensions, means to heat said devices, and means to move the articles step by step through the 55 guideway and successively into the folding box, into position for operation of said mechanism and into position for engagement with said devices, and means to receive the articles from the latter when an article 60 engaged by said devices is moved by abutment with a preceding article on a succeeding cycle of operation of the step-by-step means.
14. In a wrapping machine, a member 65 mounted for intermittent swinging movement and having a pocket in which an article and its wrapper may be positioned, means to feed articles and their wrappers to said pocket when said member is at rest in one position to partially wrap the articles, a guideway at a distance from the feeding means and with which said pocket is adapted to align when said member comes to rest in another position, means operable 70 when said member comes to rest in the second position to transfer the article from the member into the guideway to complete the wrapping except for end wrapper extensions, means to intermittently swing said member from the first to the second position and back again, mechanism to fold said 75 extensions while the article is at rest in said guideway, and connections between said mechanism and last-named means to operate the former from the latter.
15. In a wrapping machine, means to wrap articles and leave oppositely-disposed wrapper extensions at each end of the article to be folded one upon the other in overlapping relation, a guideway through which articles thus wrapped may travel intermittently in a straight line path, means to thus move the articles along the guideway, and means operable while the articles are at rest 80

- in one position to fold first one and then the other of said extensions at each end of the article, said last-named means comprising, members on opposite sides of said guideway 5 mounted to swing toward and away from the latter in a plane at right-angles to the line of travel of the articles, spaced fingers on each member adapted to enter into the guideway and simultaneously fold one ex-
tension at each end of the article, and means 10 to actuate said members so that the fingers to actuate said members so that the fingers
- on one first enter the guideway and then move back simultaneously as the fingers on the other enter the guideway, whereby the first folded extensions may be held until the other extensions are overlapped upon them and the last-named fingers are held in folded position until the article moves to another position, said guideway having means to hold the overlapped folds when the article moves into the last-named position. 15 20

ADOLPH MACH.

It is hereby certified that in Letters Patent No. 1,289,216, granted December 31 1918, upon the application of Adolph Mach, of Springfield, Massachusetts, for an improvement in "Wrapping-Machines," errors appear in the printed specification requiring correction as follows: Page 2, line 35, for the compound word "end-trucking" read *end-tucking*; page 7, line 17, for the word "advanced" read *advance*; same page, line 27, for the word "position" read *positions*; page 8, line 88, claim 1, for the word "position" read *plane*; same page, line 98, claim 2, before the word "plane" insert the word *common*; and that the said Letters Patent should be read with these corrections therein that the same may conform to the record of the case in the Patent Office.

Signed and sealed this 4th day of March, A. D., 1919.

[SEAL.]

R. F. WHITEHEAD,

Acting Commissioner of Patents.

Cl. 93—7.
